UNITED STATES PATENT OFFICE.

JAMES M. CLARK, 3d, OF BUFFALO, NEW YORK.

STARTING DEVICE FOR GAS-OPERATED MOTORS.

1,144,349.

Specification of Letters Patent. Patented June 29, 1915.

Application filed December 26, 1913. Serial No. 808,905.

To all whom it may concern:

Be it known that I, JAMES M. CLARK, 3d, a citizen of the United States, residing at Buffalo, in the county of Erie and State of New York, have invented a new and useful Starting Device for Gas-Operated Motors, of which the following is a specification.

My invention relates to an improvement in starting devices for motors operated by gas as a fuel.

The object of this invention is to provide a safe, reliable and economical starting device for motors operated by gas particularly as used in automobiles and motor cycles.

15 In carrying out this invention there is provided a gas motor equipped with a starting device consisting of an operating lever, mainspring, two or more gears, ratchets operated by the operating lever and to engage 20 the starting device with the motor, an automatic arrangement returning the starting device to starting position after spinning the motor and means to prevent injury to the motor or starting device through backfiring of the motor.

25 The invention will be fully understood from the following description taken in connection with the accompanying drawings.

In the drawings, Figure 1, is a side view 30 of the starting device in a starting position, Fig. 2, is a side elevation of the starting device with the mainspring at its extreme tension and about to spin the motor, Fig. 3, is a side view of the starting device after 35 the mainspring has contracted and the motor has been spun, Fig. 4, is a sectional view of the gears, cam, ratchet engaging with the crankshaft of the motor, showing the relative position of the motor to the 40 starting device when practical to mount the device to engage directly with the motor at the crankshaft instead of spinning the motor through intermediate gearing.

45 Standards and means for supporting and attaching the device to the motor are not shown. The design of the standards and means for installing varying with the design of the motor to which it is attached.

50 In the drawings 35 shows part of the crankshaft of a motor with ratchet 34 made fast thereto having teeth 33 on the face. A hand crank (36) (19) for spinning the motor by hand, having ratchet teeth 21 on the face to engage with teeth 33, 37 being 55 the handle of the hand crank. Teeth 21 being held disengaged from teeth 33 by spring

32 which spring also presses against gear 18 revolving on crank 19 causing ratchet teeth 17 to engage teeth 33 when gear 18 is released by cam 16 made fast to gear 24 turning on spindle 22, gear 24 being in mesh with gear 18. Stud 29 being made fast to gear 24 and connected by springs (26) (27) to trigger 25 at convenient specified places, trigger 25 being pivoted at point 28 or other convenient point near point 28. Cam 16 is rounded outward at the points 41 and 30 away from the face of gear 24 to permit of easy engagement and release of gear 18. Also attached to stud 29 is a connection 15 60 having at its opposite end from stud 29 a mainspring 12 made fast, said mainspring being of any suitable design, either a compressing or expanding spring being used as is required according to the available space in which to install, preference being had for an expanding spiral spring although I do not wish to be limited to this type of spring only.

65 At a convenient place on or near the mainspring is a connection 11, a cable 14 or other suitable means made fast to connection 11 of sufficient length to reach to the trigger 25 when mainspring 12 is at its extreme tension, said cable 14 being made fast to the 70 trigger at the trigger end of said cable. Also made fast to the mainspring 12 at the end to which connection 11 is attached to spring 12, is a connection also attached to stud 8 located on ratchet wheel 6. The teeth 7 on ratchet wheel 6 engaging with pawl 4 which prevents ratchet wheel 6 from turning rearwardly and a pawl 2 attached to and operating with lever 3 operated by hand or foot at point 1, said lever (3) (5) and 75 ratchet wheel 6 turning upon a suitable shaft 45. The enlarged part of the lever being designated as 5 to present a good face for ratchet wheel to rest against or lever 3 may turn upon the shaft allowing the 80 ratchet wheel to rest against the standard itself, 9 being the standard supporting the ratchet wheel 6 and relative parts.

I do not wish to be limited to attaching the device to the motor only as described in 85 the specification as motors of different manufacture vary in design. The gear 18 may transmit the power to the crankshaft 35 through intermediate gearing, chains or other convenient means and not be mounted 90 in line with the axis of the crankshaft 35.

To operate this device and spin the motor,

the operator using the device as described in Figs. 1, 2, 3, 4, starts with the device in position as illustrated in Fig. 1, pushing lever 3 forward by hand or foot at 1 to a stop not shown that limits the length of the stroke, giving successive pushes bringing stud 8 into position as shown in Fig. 2, by means of pawl 2, pawl 4 holding ratchet wheel 6 in position and preventing ratchet wheel 6 from turning rearward.

It will be seen that by the above operations the maximum tension has been put upon mainspring 12, taking up the slack in connection 14 and causing trigger 25 to move slightly from position 25* to position 25 in Fig. 2 thus releasing stud 29 which permits mainspring 12 by means of connection 15 to pull stud 29, gear 24 and relative parts into position as shown in Fig. 3, which is approximately one-half a turn of gear 24. As gear 24 starts to turn, cam 16 to which it is made fast releases gear 18 at point 41 on cam 16 which gear 18 is in mesh with gear 24 allowing gear 18 to be pushed out of line with gear 24 by spring 32 and causing ratchet teeth 17 to engage ratchet teeth 33 turning ratchet 34 and relative parts of the motor such as crankshaft 35, in the same direction as gear 18 until the device reaches position as shown in Fig. 3, at which time cam 16 engages at point 30 with rim of gear 18 forcing gear 18 into line with gear 24 which also releases ratchet 17 from teeth 33 allowing the motor if started to continue to run independently of the starting device. A slight push on the lever 3 brings stud 8 past the center allowing spring 27 which has now a tension to bring stud 29 past the center allowing spring 26 to exercise a pull upon stud 29 and bring stud 29 and relative parts back into engagement with trigger 25 as shown in Fig. 1, which is the starting position when the starting of the motor with the starting device is to be repeated.

From position as shown in Fig. 3, to position as shown in Fig. 1, the cam 16 presses against gear 18 keeping it from becoming engaged with motor through ratchet teeth 17.

Should the motor backfire as motors sometimes do because of the spark being too far advanced and the motor consequently starting in the opposite direction to which it is intended to run and teeth 17 and 33 are engaged, the motor turns the mechanism of the device backward causing the stud 29 to strike against the rounded point 38 on trigger forcing trigger back slightly and allowing stud 29 to engage with notch 39 which is the starting position of the gears and cam. The point 41 on cam 16 having engaged with gear 18 and disengaged teeth 17 from teeth 33 at approximately the same time that stud 29 engaged

with notch 39. This arrangement of the various parts preventing the starting device from being injured and from causing injury to the motor or operator of the device.

Should it be desired or necessary through any cause to spin the motor by hand in the usual manner that motors are spun with the hand crank instead of employing the starting device, the operator grasps the handle 37 pushes against it causing 36 and 19 to press against spring 32 by means of the flange 72 allowing teeth 21 to engage with teeth 33 and by turning the crank 37, 36, 19 the motor is turned as when no starting device is used. Crank 19 and relative parts being independent of the starting device excepting as already described.

Spring 32 has the double function of holding crank 19 from becoming engaged with crankshaft 35 through relative parts of each excepting when desired and also causing gear 18 to become engaged with crankshaft 35 through their relative parts when gear 18 is released by cam 16.

What I claim is:

1. In a starting device for gas operated motors, an engine shaft, a rotatable gear, a ratchet wheel spaced therefrom, a stud on said gear, a pivoted member adapted to engage the stud, springs connecting the stud to the pivoted member, means connecting the gear and ratchet wheel, including a coil spring, means for rotating the ratchet wheel to place said coil spring under tension, telescoping links connecting said coil spring and pivoted member whereby said stud is released from the pivoted member when the spring has attained a predetermined tension, and means operated by the rotation of said gear wheel to engage and rotate said engine shaft.

2. In a starting device for gas operated motors, in combination with an engine shaft, a rotatable gear wheel, a stud and cam on one face thereof, a pivoted member adapted to engage said stud, a ratchet spaced from said gear wheel, means connecting said ratchet and gear including a coil spring, a pawl for operating the ratchet to place the spring under tension, a connection from said spring to the pivoted member to disengage the pivoted member from the stud after the spring has reached a predetermined tension, slideable means connecting the rotatable gear to the engine shaft, the engagement and disengagement of said last mentioned means with said shaft being controlled by said cam.

3. In a starting device for gas operated motors, an engine shaft having a ratchet clutch member, a cranking shaft in longitudinal alignment with said engine shaft, a gear wheel slideable on said cranking shaft having a ratchet adapted to engage said clutch member, a spring tending to engage

said ratchets, a rotatable gear wheel engaging the slidable gear wheel, a cam on one face thereof to control the engagement and disengagement of said ratchet, a ratchet wheel, means connecting the rotatable gear and ratchet wheel, including a coil spring, a pawl for operating said ratchet wheel to place said coil spring under tension, and means for releasing the coil spring at a 10 predetermined tension whereby the second

mentioned gear is rotated and the slidable gear is permitted to engage with and is disengaged from the engine shaft.

In testimony whereof I affix my signature in the presence of two witnesses.

JAMES M. CLARK, 3d.
